UNITED STATES PATENT OFFICE.

GEORGE SAXON, OF OPENSHAW, ENGLAND.

DESIGN FOR A FRAME FOR FORGING-MACHINES.

SPECIFICATION forming part of Design No. 26,440, dated December 22, 1896.

Application filed August 10, 1896. Serial No. 602,363. Term of patent 7 years.

To all whom it may concern:

Be it known that I, GEORGE SAXON, a subject of the Queen of Great Britain, residing at Openshaw, near Manchester, in the county 5 of Lancaster, England, have invented and produced a new and original Design for a Frame for Forging-Machines, of which the following is a specification.

This design consists in a new form of frame 10 for a forging-machine.

The form is clearly shown by the annexed drawings, of which—

Figure 1 is a side view; Fig. 2, an end view, 15 and Fig. 3 a plan with the sides of the frame in section.

The design consists of the T-shaped side

piece a , having perforations at a' and a'' , and a base portion b , extending on each side of the bottom of the T-shaped sides, said base-piece having ribs b' on each side of the T-bottom and vertically-faced parts b'' , provided with perforations. The base portion is slotted at b^1 .

I claim—

The design for a forging-machine frame 25 herein shown and described.

In witness whereof I have hereunto set my hand in presence of two witnesses.

GEORGE SAXON.

Witnesses:

CHARLES A. DAVIES,
JNO. HUGHES.
